UNITED STATES PATENT OFFICE.

GEORGE RAYMOND AND ALBERT RAYMOND, OF CHICAGO, ILLINOIS.

ATTRITION-MILL.

SPECIFICATION forming part of Letters Patent No. 403,215, dated May 14, 1889.

Application filed June 27, 1888. Serial No. 278,369. (No model.)

To all whom it may concern:

Be it known that we, GEORGE RAYMOND and ALBERT RAYMOND, citizens of the United States, residing at Chicago, in the county of Cook and State of Illinois, have invented certain new and useful Improvements in Attrition-Mills, of which the following is a specification.

Our invention relates to that class of attrition-mills wherein the grinding or reduction of the material is accomplished by the impact of the fragments upon each other and the attrition of such fragments one by the other, or, in other words, to that class of machines wherein the material under treatment forms the grinding-surfaces; and the object of our invention is to improve the construction and operation of such machines, as hereinafter described and claimed.

20 In the accompanying drawings, Figure 1 is a partial view in front elevation of an attrition-mill embodying one form of our improvements. Fig. 2 is a vertical cross-section on line 2 2 of Figs. 1 and 3. Fig. 3 is a plan view of the lower portion of the machine, showing one of the revolving heads thereof in cross-section. Fig. 4 is a transverse sectional view on line 4 4 of Figs. 1 and 3. Fig. 5 is a partial rear elevation of a machine embodying some of the features shown in the former figures, and part of the rear wall being broken away to expose portions of the interior construction. Fig. 6 is a vertical cross-section on line 6 6, Fig. 5; and Fig. 7 is a detail showing in vertical section a revolving grinding-head provided with a removable grinding-ring.

30 The principal mechanical parts of our improved attrition-mill, as shown in the drawings, are constructed and arranged as follows: A base, A, supports the superstructure and rotatable shaft of the mill, and constitutes the lower section of the casing inclosing the operating parts. The base A is flat on its under surface to form a base for the machine and concave on its upper surface, whereby to constitute one portion of the grinding-chamber. Said base has at its upper extremity outwardly-projecting bolt-flanges a, to which

40 are secured by bolt-flanges b segmental curved plates B, which form a part of the

housing for the grinding-heads, and connected to these curved plates and integrally therewith are vertical extensions C, which form the front walls of a separating-chamber above the heads. Interposed between these segmental pieces B are feed-hoppers D, of which in the present example there are three, and which communicate with the pulverizing-chambers.

6c

The rear wall of the separating-chamber is marked E, and it has a vertical portion and an inclined extension forming a throat of the discharge-pipe G. The separating-chamber is inclosed at the top by a plate or covering, F, an extension of which, f, forms another portion of the throat of the discharge-pipe G. A rotatable shaft, H, is journaled in suitable boxes centrally of the pulverizing-chamber, and has secured thereon one or more revolving heads I. Said heads, as shown in Figs. 2, 3, and 4, comprise a hub, i, a web, j, and a flanged periphery, J, projecting laterally from the web j on each side. These heads are secured to rotate intermediate the hopper-openings and beneath the curved segmental parts B of the casing. They are all set on shaft H, and hence all revolve in the same direction. Shaft H may be rotated by the application of belts to its pulleys h. Semi-cylindrical housings K inclose the upper parts of the revolving heads and protect the periphery of the same from the material to be reduced. The interiors of the hoppers of the pulverizing-chambers and of the rear wall of the separating-chamber are protected by a lining, L, which is made in three parts, as shown, or otherwise suitably constructed. These linings are fitted to the interior wall of the casing and have flanged edges l extending inwardly in close proximity to the peripheries of the heads or beaters, thus forming in conjunction with the casing and heads or beaters annular chambers around the lower portion of the machine. Air-ducts M are employed to supply air to the separating-chamber, and for convenience these may be located at the rear of the hoppers and constitute one wall thereof, Fig. 2. These air-ducts M communicate by the perforations m with the separating-chamber, and the air may also, in some conditions of the grinding, pass out of

the lower end of the ducts and into the pulverizing-chamber.

N represents the separating-chamber, and O the pulverizing-chambers.

5 It will be understood that the separating-chamber communicates with each of the pulverizing-chambers, and that in operation a suction-fan is connected to the discharge-pipe G.

10 The front wall of the separating-chamber is lined by a corrugated chilled-iron plate, P. In the operation of the machine this plate will receive the violent impact of the particles undergoing reduction, and therefore should 15 be quite heavy, so as to withstand the wearing effect of these particles. The upper part of the machine is hinged to the lower at Q, whereby when the bolts joining the upper and lower parts at the bolt-flanges a b are re- 20 moved ready access may be had to the wearing parts of the machine. Openings are formed at R through the base A below the heads for the discharge of the reduced material, Fig. 2, accumulating there.

25 In operation the material is fed in through the hoppers D and passes directly into the pulverizing-chambers O between the revolving heads. By reference to Fig. 3 it will be seen that said chambers O are greater in di- 30 ameter than the revolving heads, owing to the shape of the linings L, and an important result is secured thereby, viz: The material, being fed continuously through the hoppers D, will accumulate in the pulverizing-chambers 35 O and in the chambers of the revolving heads until the entire space is filled. During this filling operation the material lying upon the bottom and sides of the chamber O will be at rest, while the material within the chambers 40 of the revolving heads will be in motion, and the attrition of the fragments will follow from the impact of the moving mass upon the stationary mass. As the operation proceeds, a constant stream of mingled pulverized and 45 unpulverized material will be thrown out of the rear part of the pulverizing-chambers into the separating-chamber. During the operation a constant supply of air will be drawn by the action of the fan through the

50 air-ducts into the separating-chamber, whereby the pulverized material will be carried out through the discharge-pipe G, while the particles of material which are too large or heavy to be moved by the air-blast will drop back 55 again into the pulverizing-chamber. Any material which may find its way through the joints between the linings L and the revolving heads in the construction exhibited in Figs. 1 and 2 will pass out at the openings R in the 60 base A.

In the type of machines shown in Figs. 5 and 6 we have introduced a modification, which consists in providing air-ducts S, communicating through the curved plates B, with 65 the chambers or spaces T between the periphery of the heads and the base A. By this means air will be drawn by the action of the

fan through said chambers, and any material which may accumulate therein can be drawn out and discharged into the separating-chamber, as shown in Figs. 5 and 6. By this arrangement all danger of the shutting off of the supply of air by the stoppage of the perforations m is avoided, as constant currents of air are permitted to circulate under the 75 heads and pass into the separating-chamber without passing through the material undergoing comminution. In this modified construction the perforations m, to admit air directly from the air-duct M to the separating-chamber, are dispensed with, and the base is not provided with the openings R, as all the material is discharged through the discharge-pipe G. To assist in removing dust from the chamber T beneath the heads, lifts U are set 80 transversely thereon, which, rotating close to the casing, will scrape any material out of the chamber and, assisted by the fan, will discharge it into the separating-chamber.

Deflecting plates V, Figs. 5 and 6, may be 90 placed in the opening above the chambers T, which will deflect the fine material drawn from the said chamber outwardly into the separating-chamber.

In Fig. 7 I have shown a revolving head 95 double cone-shaped in form and a lining, L, made to conform to the rear wall of the head. This head may be constructed in one piece or in two parts, X and Y, the latter having a bolt-flange, y, fitted to the inner side of the other 100 portion, to which it is secured by bolts, so that when it becomes worn it may be replaced without disturbing the other parts, which sustains no wear. It will be observed that the parts X and Y are frustums of cones, 105 whose bases are joined together, thereby forming a pocket to receive and retain the material to be acted upon. The form of head shown in this figure is adapted for use in the end of the chamber, but when used in the 110 body of the chamber it will be made double or with recesses on both sides.

It is apparent that in a machine organized as above described any number or width of pulverizing-chambers may be provided by the 115 use of the recessed heads, as said heads may be set at any distance apart desired, the linings being made to correspond. When the heads are recessed on both sides, as shown, one head may serve as means for operating the material on one side of two chambers formed on either side of it. One desirable result which we accomplish by our improved construction above described is that the pulverized material in the type of machine shown in Figs. 5 120 and 6 is confined entirely within the outside 125 casing or shell of the machine until finally discharged through the discharge-pipe G, thus preventing not only the waste of the material, but the annoyance and damage caused by the 130 escape of the pulverized material.

We claim—

1. In an attrition - mill having a circular pulverizing-chamber, one or more recessed

heads mounted within said chamber upon a rotatable shaft, a feed-opening communicating with one side of the pulverizing-chamber, a separating-chamber communicating with the side of said pulverizing-chamber opposite the feed-openings, and an air-duct communicating with the pulverizing-chamber, substantially as described.

5 2. In an attrition-mill having a circular pulverizing-chamber, rotatable recessed heads mounted upon a common shaft within the chamber, feed-hoppers communicating with one side of the pulverizing-chamber, and a separating-chamber communicating with the side of said pulverizing-chamber opposite the feed, and air-ducts communicating with the pulverizing-chamber, substantially as described.

10 3. In an attrition-mill having a circular pulverizing chamber or chambers, a rotatable shaft mounted centrally within said chambers and carrying heads recessed to receive material to be operated upon and adapted by their rotation to pulverize such material by its attrition upon the stationary material within the pulverizing-chamber, and a separating-chamber communicating with the pulverizing-chamber, said chamber having a hard metallic lining to receive the impact of the

15 30 4. In an attrition-mill having a circular pulverizing-chamber within which are

mounted upon the same shaft rotatable recessed heads of less diameter than said chamber, flanged linings bridging the space between said heads and the wall of the chamber, feed-hoppers communicating with one side of the pulverizing-chamber, a separating-chamber communicating with the side of the pulverizing-chamber opposite the feed-entrance, and air-ducts communicating with the pulverizing-chamber, substantially as described.

5 5. In an attrition-mill having a circular pulverizing-chamber within which are mounted upon the same shaft rotatable recessed heads of less diameter than said chamber, flanged linings secured to the peripheral wall of the chamber between the heads, the flanges bridging the vertical space between the heads and the wall, whereby passages are formed between the heads and the wall, and air-ducts communicating with said passages, substantially as described.

10 6. A head for attrition-mills, double-cone-shaped in form, whereby to provide a pocket or recess to contain material to be operated upon, substantially as described.
